Patented Aug. 11, 1959

185,884

COMBINATION BOTTLE AND ASH TRAY HOLDER

Thomas Edward Cross, Des Moines, Iowa

Application February 6, 1959, Serial No. 54,499

Term of patent 14 years

(Cl. D58—26)

Fig. 1

Fig. 3

Fig. 1 is a perspective view of a combination bottle and ash tray holder showing my new design;

Fig. 2 is a top plan view of the same; and

Fig. 3 is a side elevational view of the same.

I claim:

The ornamental design for a combination bottle and ash tray holder, as shown.
